HANGER FOR LITTER BAGS AND THE LIKE

Ethan C. Grant, P.O. Box 2091, Salem, Oreg. 97308

Filed July 23, 1973, Ser. No. 381,526

Term of patent 14 years

Int. Cl. D8—08

U.S. Cl. D7—193

FIG. 4

FIG. 5

FIG. 6

FIG. 7

FIG. 1 is a perspective view of a hanger for litter bags and the like, showing my new design.

FIG. 2 is a left side elevational view;

FIG. 3 is a left side elevational view in unlocked position;

FIG. 4 is a top plan view taken on line 4—4 of FIG. 2;

FIG. 5 is a bottom plan view taken on line 5—5 of FIG. 2;

FIG. 6 is a rear elevational view taken on line 6—6 of FIG. 2; and

FIG. 7 is a front elevational view taken on line 7—7 of FIG. 2.

I claim:

The ornamental design for a hanger for litter bags and the like, as shown.
